DIE HEAD

Filed May 12, 1926

Inventor
Albert F. Breitenstein
Seymour Parce & Nichols
Attns.

UNITED STATES PATENT OFFICE.

ALBERT F. BREITENSTEIN, OF NEW HAVEN, CONNECTICUT, ASSIGNOR TO THE GEOMETRIC TOOL CO., OF NEW HAVEN, CONNECTICUT, A CORPORATION.

DIE HEAD.

Application filed May 12, 1926. Serial No. 108,492.

Fig. 1 is a view mainly in side elevation and partly in longitudinal section of a die-head embodying my invention.

Fig. 2 is a plan view thereof with a part of the operating-sleeve broken away.

Fig. 3 is a view thereof in front elevation.

Fig. 4 is a detached view in side elevation of one of the chasers.

Fig. 5 is a similar view in front elevation 10 of one of the chaser-retracting plungers.

Fig. 6 is a similar view thereof, partly in side elevation and partly in longitudinal central section.

My invention relates to an improvement in 15 die-heads of the class having radially-movable chasers forced inwardly into their cutting positions by an operating-member having chaser-operating, chaser-retracted, and chaser-clearance positions, the object being 20 to produce a simple, convenient and effective tool constructed with particular reference to the mechanism employed for retracting the chasers.

With these ends in view, my invention consists in a die-head having chasers, an operating-member therefor, radially-movable spring actuated plungers for the respective chasers, and means carried by the plungers and engaging with the chasers in position to 30 exert outward draft thereupon in such manner as to permit the chasers to be radially removed from the die-head independently of the plungers.

My invention further consists in a die-head 35 characterized as above and having certain details of construction and combinations of parts as will be hereinafter described and particularly pointed out in the claims.

In carrying out my invention as herein shown, it is embodied in a die-head of standard construction having a skeleton-body 10 provided with a shank 11 by means of which it is mounted for use. The said body mounts a chaser-operating member in the form of a 40 sliding operating-sleeve 12 adjusted in position for varying the cutting diameter of the die-head in the ordinary manner by means of an adjusting-nut 13 threaded upon the shank 11, the said sleeve having a forward or operating position, an intermediate or chaser-retracted position, and a rear or chaser-clearance position.

The said body 10 is provided at its forward 55 end with four equidistance radial slots 14 respectively receiving one of four correspond-

ing chasers 15, each of which is provided with cutting-teeth 16 at its inner end, and a bevel 17 at its outer end for co-action with a cam-surface 18 formed by notching the inner edge of the forward end of the sleeve 12.

To provide for the radial retraction of the chasers 15 into their retired or non-cutting position, I form the inner rear corner of each with an inwardly-opening notch 19 for the reception of a hook 20 at the lower end of 60 each of four spring-arms 21, the upper end of each of which terminates in a centrally-perforated plate 22 secured by a rivet 23 to the upper end of a cylindrical chaser-retracting plunger 24 located in a plunger-chamber 25 65 formed in the body 10 at a point directly back of each of the slots 14 therein and connected with the slots by a passage 26 through which the hook 20 passes for entrance into the notch 19 of the chaser and in which the hook is free 70 to move radially with its complementary plunger 25. For the actuation of the said plunger, each is provided with a socket 27 for the reception of a helical plunger-retracting spring 28 resting upon the bottom of its 75 chamber 25.

Normally, the chasers are retained in the die-head against the outward thrust of the springs 28 by the engagement of their outer ends with the sleeve 12 when in its operating 80 position, as shown by full lines in Figs. 1 and 2, and when in its intermediate or chaser-retracted position, as shown by broken lines 29 in Fig. 1.

By preference, the spring-arms 21 are set 85 away from the plungers 24, as shown in Fig. 6, to make a sufficient frictional contact with the inner edges of the chasers to prevent them from falling out of the die-head by gravity or under vibration when the sleeve is in its 90 chaser-clearance position, while the plungers themselves are prevented from falling out by the forward edge of the sleeve in such position. On the other hand, the spring-arms, by 95 their frictional engagement with the inner edges of the respective chasers, permit the chasers to be individually inserted into the die-head and retained in place, thus avoiding the necessity of manually holding the four of them concurrently in place until the 100 operating-sleeve is engaged with their beveled outer ends.

By coupling the chasers and plungers in the manner described, the chasers may be 105 radially-removed independently of the plunger- 110

ers when the chaser-operating sleeve occupies its chaser-clearance position.

A device for yieldingly retaining the chasers in the die-head is not broadly claimed herein but is made the subject-matter of a co-pending application, Serial No. 107,645, filed May 8, 1926, by Ewald A. Barteit.

I claim:

1. A die-head having radially-movable chasers, each formed at its inner rear corner with an inwardly-opening notch, a chaser-operating member having chaser-closing, chaser-retracted, and chaser-clearance positions, radially-movable spring-actuated chaser-retracting plungers, arms carried thereby and extending inwardly beyond the inner ends thereof and adapted to engage with the notched inner ends of the chasers in position to exert outward draft thereupon and to permit the chasers to be radially removed independently of the plungers when the chaser-operating member is in its chaser-clearance position.

2. A die-head having chasers, each formed at its inner rear corner with an inwardly-opening notch, a sliding chaser-operating sleeve co-acting with the outer ends of all of the chasers and adapted to assume chaser-closing, chaser-retracted, and chaser-clearance positions, radially-movable, spring-actuated plungers mounted in the die-head, and hooked arms carried by the said plungers and extending inward beyond the inner ends thereof and entering the said notches of the chasers for coupling the same to the plungers, whereby the same exert outward draft thereupon and whereby the chasers are radially removable independently of the plungers when the said operating-sleeve is in its chaser-clearance position.

3. A die-head having radially-movable and radially-removable chasers, a chaser-

operating member having chaser-closing, chaser-retracted, and chaser-clearance positions, radially-movable spring-actuated chaser-retracting plungers, and yielding means frictionally engaging directly with the bodies of the chasers for preventing them from dropping out of the die-head by gravity when the chaser-operating member is in its chaser-clearance position and engaging with the chasers for normally exerting positive outward draft upon them.

4. A die-head, having radially-movable and radially-removable chasers, a chaser-operating member having chaser-closing, chaser-retracted, and chaser-clearance positions, radially-movable spring-actuated chaser-retracting plungers, and spring-arms carried by the said plungers, frictionally engaging with the chasers for preventing them from dropping out of the die-head by gravity when the chaser-operating member is in its chaser-clearance position, and shaped to engage with the chasers for normally exerting positive outward draft upon them.

5. A die-head, having radially-movable and radially-removable chasers, each formed at its inner rear corner with an inwardly-opening notch, a chaser-operating member having chaser-closing, chaser-retracted, and chaser-clearance position, radially-movable spring-actuated chaser-retracting plungers, and spring-arms carried by the said plungers and frictionally engaging with the chasers for preventing them from dropping out of the die-head when the chaser-operating member is in its chaser-clearance position, and the said arms extending into the notches of the chasers for normally exerting positive outward draft upon them.

In testimony whereof, I have signed this specification.

ALBERT F. BREITENSTEIN.
